Sketches New Design for Staircase

Back of a Drawing done

16209 *N. P. Peeks new design for sides & back of a cooking stove. Jan. 23 - 1849*

Plate. 2.

10.209 J. P. Peck, M. D. Design for Sides & Ends of a Coking-stove Jan 23 1849

Plate 3

Des. 209

W. P. Peck, Springfield, Mass., letters patent No. 209 dated Jan 23, 1849.
The schedule referred to in these letters patent and making
part of the same
To all persons to whom these presents shall come: Be it known
that I, N. P. Peck of Springfield in the County of Hampden and
State of Massachusetts, have invented or produced a new and
original design for the sides and back of a cooking stove
and that the following description taken in connection with
the accompanying drawings herein referred to, is a full
and exact specification of the same.

The new design is represented in this accompanying plate
of drawings, of which plate 1 is an elevation of one side of the
cooking stove and plate 2 a similar view of the back.
fig. 1, pl. 3, being a section on the line A.B. pl. 1, and fig. 2,
pl. 3, a section on the line C.D. pl. 2, said figures showing
the contours of the ornaments on the said sides and back.

The side plate is of the shape shown in plate 1 and
has a raised moulding all around it near its edges, as
shown at a a a a a a, in said pl. 1, and in section in
fig. 1, pl. 3. There are three doors on this side plate
all of which have around their sides an elaborate mould-
ing as shown at b b b b, c c c c and d d d d, the first
two named being rectangular, and the last named, or
oven door being nearly so, having necessarily, a short
recutting curve at one corner as shown in the drawings
to give free play to the other doors. Over the top of the
oven door is a rectangular space, surrounded by a mould-
ing c c c c. The surfaces enclosed within the mouldings

above referred to, about this door and rectangular space are all similarly ornamented as follows: viz. with four leaves f.f.f.f. having sunken mid ribs arranged within a sunken circle g.g.g. Around this circle are cast a quantity of diamonds arranged in four triangles as shown at h.h.h.h. in pl. 1. and from the sides of these triangles radiate in every direction towards the sides of the surrounding mouldings, the elongated triangles are also shown at i.i.i.i. &c.

The back of this stove is ornamented similarly to the sides & plates above described. There is on the same, over piping the centre, a rectangular moulding or k.k.k.k. enclosing leaves, a sunken circle, diamonds in triangles and radials, & it is exactly like those above referred to and indicated by the same letters.

On each side of this last named rectangular space k.k.k.k. is a pilaster surrounded by a moulding, l.l.l.l. and having a plain space m.m.m.m. at the centre enclosed between parallel sides and circular ends as shown in fig. 2. the outer face of the casting in this space being swelled out a little transversely as shown in fig 2. pl. 3. Between the sides of this space, and the moulding l.l.l.l. are cast the parallel wedge shaped ribs m.m.m.m. &c and between the circular ends of said space, m.m.m.m. and the ends of the above said moulding l.l.l.l. are the radial ribs o.o.o.o. like those before described.

Des. 209

Having thus described my new design I do state my claim as follows

What I claim as my invention or production and do pur to have secured to me by letters patent is the combination of ornamental mouldings and carvings or configurations herein above described and represented in the drawings, for the side and back plates of a cooking stove.

In testimony that the foregoing is a true description of my said invention or production I have hereunto set my signature this thirtieth day of October A.D. 1868

Witnessed
